UNITED STATES PATENT OFFICE.

ROY F. SETTLES, OF HELENA, MONTANA.

TOY GUN.

1,250,523.

Specification of Letters Patent. Patented Dec. 18, 1917.

Application filed June 30, 1917. Serial No. 177,911.

To all whom it may concern:

Be it known that I, ROY F. SETTLES, a citizen of the United States, residing at Helena, in the county of Lewis and Clark and State of Montana, have invented certain new and useful Improvements in Toy Guns, of which the following is a specification, reference being had to the accompanying drawings.

- 10 This invention relates to toy guns, and particularly to guns on the order of pop guns, wherein a cork or like article is projected from the gun by the pressure of air behind the projectile.
- 15 The general object of my invention is the provision of a very simple, easily constructed and easily operated gun of this character, wherein the parts may be readily assembled.
- 20 A further object is to so construct the gun that it may be loaded after the manner of a pop gun, that is, that the air compressing piston may be retracted by a retracting slide on the barrel of the gun, the slide then being moved forward, which permits the plunger to be projected under the action of a spring by operating the trigger.

Other objects have to do with the details of construction and arrangement of parts, as will appear more fully hereafter.

My invention is illustrated in the accompanying drawings, wherein:

Figure 1 is a longitudinal sectional view of a gun constructed in accordance with my invention;

Fig. 2 is a section on the line 2—2 of Fig. 1;

Fig. 3 is a fragmentary vertical longitudinal section through a portion of the stock and the trigger mechanism;

Fig. 4 is a section on the line 4—4 of Fig. 1;

Fig. 5 is a section on the line 5—5 of Fig. 1;

Fig. 6 is a section on the line 6—6 of Fig. 1.

Referring to these drawings, it will be seen that my gun comprises a stock consisting of the butt 10 and the fore stock 11, the butt and fore stock being formed of one piece of wood. The fore stock is grooved to support the barrel and is slotted as at 12 for the trigger. An anchor screw 13 passes through the fore stock and is adapted to hold the trigger guard in place upon the fore stock.

The barrel 14 is, of course, tubular and is provided with the longitudinally extending oppositely disposed slots 15, which extend to the rear end of the barrel. The slots terminate short of the rear end of the barrel, and a tang 16 is operatively engaged with the rear end of the barrel, this tang extending rearward and being attached by a tang screw 17 to the stock.

Extending over the slots 15 are the transversely curved guards 18, which are open at their opposite ends and form guides. Slidingly mounted upon the barrel 14 is a sleeve 19, which closely surrounds the barrel and slides easily thereon and to this sleeve are attached the rearwardly extending rods 20, which are semi-circular in cross section and fit within the guides 18. To the under face of the sleeve 19 is attached a hand grip 21, which may be held in place upon the sleeve by means of a screw 22, this hand grip being preferably made of wood and being transversely corrugated or roughened so that it may be readily gripped. Preferably this hand grip is formed with ribs 23 and the rods 20 at their forward ends are grooved to receive these ribs.

Disposed within the barrel 14 is a plunger rod 24, the forward end of which carries a piston or plunger comprising two confronting washers 25 with an intermediate leather cup 26, the washers and the cup being held in place on the plunger rod by means of a nut 27, engaging the screw-threads on the rod. The rear end of the plunger rod 24 is transversely slotted as at 28 and wedged in place within this slot is a transversely extending block 29, which constitutes a stop and which extends out through the slots 15 of the barrel and into the path of movement of the rearwardly extending rods 20. A guide washer 30 is also mounted upon the plunger rod rearward of the slot 28 and rearward of this guide washer, the rod 24 is formed with a recess or notch 31. The rear extremity of the rod 24 is upwardly beveled as at 32.

Disposed within the barrel just in advance of the slots 15 is a guide washer 33 through which the plunger rod 24 slides, this guide washer being provided with a helical cushioning spring 34. The cushioning spring is mounted upon the guide washer concentric to the central opening and is soldered in place within the barrel or otherwise supported therein, in any suitable manner. The

transversely extending stop 29, upon a projection of the plunger, is adapted to engage with this spring and thus acts to limit the forward movement of the plunger. Surrounding the plunger and bearing against the plunger head or piston, is a coiled plunger spring 35, which at its rear end bears against the guide washer and at its forward end bears against the head of the plunger. It will be obvious that when the plunger is retracted, the spring will be compressed. Disposed at the rear end of the barrel is a trigger 36, pivoted upon a transverse pivot pin 37, there being a perforated ear for this purpose, the body of the trigger being formed with a forwardly extending detent 38 adapted to engage with the notch 31 on the plunger rod. A spring 39 engages with the trigger and urges it in a direction to carry the detent 38 upward. The trigger is mounted upon a trigger crown 40 formed of a transversely curved strip of metal soldered or otherwise attached to the rear of the barrel and perforated for the passage of the pivot pin 37. Springs 41 upon the pivot pin keep the trigger in a central position. The trigger extends out through a slot 42 on the underside of the barrel and the stock is provided with the usual trigger guard 43. As a projectile I have illustrated a cork 44, which may be connected to the gun by means of a cord 45. Surrounding the barrel are the collars 46 and 47. The collar 46 is soldered or otherwise disposed upon the barrel just forward of the ends of the guides 18 and forms a stop limiting the rearward movement of the hand grip and the sleeve 19, while the collar 47 is disposed adjacent the forward end of the barrel in a position to act as a stop for the slide on its forward movement. Each of the collars 46 and 47 is provided with a notch 48, which forms a seat or simulates a seat. A loop 49 may also be formed upon the collar 47 to which the string 45 may be connected. It will be noticed from Fig. 3 that the trigger is provided with an upwardly extending finger 50, which limits the movement of the trigger under the action of the spring 39. It will be obvious that with a gun of this kind, the "loading" of the gun is secured by shifting the slide 19 and the hand grip 21 rearward until the rear end of the plunger is engaged by the trigger. The cork or other projectile is then forced into the barrel and when desired the trigger is pulled, whereupon the spring 35 urges the plunger forward and projects the cork with great force and considerable noise. It is obvious, of course that other projectiles besides corks may be used and that they may not be attached to the gun by means of a string. The action of loading the gun is practically the same as that in a pop gun and is, therefore, particularly attractive to children. The for-

ward projection of the plunger under the action of the plunger spring is cushioned by the stop 29 coming in contact with the cushioning spring 34, thus preventing too great a jar on the piece by the sudden stoppage of the plunger. The component parts of this gun may be readily and cheaply made and may be easily assembled.

Having described my invention, what I claim is:—

1. A toy gun comprising a stock, a longitudinally slotted barrel, a plunger disposed within the barrel, and having a plunger rod, a spring urging the plunger forward, a trigger detachably engaging the plunger rod and holding the plunger in a retracted position against the action of the spring, a stop carried by the plunger rod and extending through said slot in the barrel, and a slide mounted upon the barrel and operatively engaging with said stop upon a rearward movement of the slide to thereby cause the retraction of the plunger and plunger rod into engagement with the trigger, said slide being independently movable forward upon the barrel after the plunger is engaged with the trigger.

2. A toy gun comprising a barrel having longitudinally extending slots at its rear end, a stock supporting the barrel, a plunger mounted within the barrel and having a plunger rod formed at its rear end with a detent notch, a spring urging said plunger and plunger rod forward, a trigger mounted on the stock and adapted to engage the rear end of the plunger rod when the plunger is retracted against the action of the spring, a stop member mounted on the plunger rod and extending transversely through said slots in the barrel, and a slide mounted upon the barrel, shiftable rearward thereon in engagement with said stop member to thereby shift the plunger rod rearward into engagement with the trigger, the slide being independently movable forward.

3. A toy gun comprising a stock, a barrel mounted in the stock having oppositely disposed longitudinally extending slots, guide members arching over said slots, a plunger mounted in the barrel and having a plunger rod formed at its rear end with a detent notch, a member extending transversely through the plunger rod and through said slots, and disposed within the guides, a trigger disposed in the rear end of the barrel and adapted to engage the notch on the plunger rod, a sliding member mounted upon the barrel and having rearwardly extending rods disposed in said guides and adapted to engage the transversely extending member on the plunger rod, and a spring surrounding the plunger rod and urging the plunger forward when the trigger is released.

4. In a toy gun, a barrel, a plunger therein having a plunger rod, a guide washer mounted upon the rear end of the plunger rod, and a centering washer carried by the 5 barrel and through which the plunger rod passes.
5. In a toy gun, a barrel, a spring actuated plunger therein, a stop mounted upon the plunger, a spring urging the plunger 10 forward, a centering washer through which the plunger passes, and a spring carried by said centering washer and acting as a cushion against which said stop impacts when the plunger is projected.
- 15 6. A toy gun including a stock, a longitudinally slotted barrel mounted upon the stock, a plunger disposed within the barrel and having a plunger rod formed at its rear end with a detent, a guide washer 20 mounted upon the plunger rod, a transversely extending stop on the plunger rod forward of the washer and extending through said slots, a spring surrounding the plunger rod and bearing against the 25 plunger and urging said plunger forward, guides extending over said slots in the barrel and into which said stop projects, a sleeve surrounding said barrel and having longitudinally extending rods disposed in 30 said guides and adapted to bear against the transversely extending stop when the sleeve is shifted rearward, to thereby retract the plunger against the force of said spring, a guide washer mounted within the barrel and through which the rear end of the spring bears, a cushioning spring mounted upon the guide washer and 35 receiving the impact of said transversely extending stop, a trigger mounted in the barrel and projecting through the sleeve and having a detent engageable with the 40 detent notch on the rear end of the plunger, and stop collars mounted upon the barrel and limiting the movement of the slide in either direction.
8. In a toy gun, a barrel, a transversely arched crown plate disposed within the barrel, a trigger disposed within the crown plate, a pivot pin passing through the trigger and pivotally supporting it, and springs on each side of the trigger and surrounding the pivot pin and resisting lateral movement of the trigger.

In testimony whereof I hereunto affix my signature in the presence of two witnesses.

ROY F. SETTLES.
